UNITED STATES PATENT OFFICE.

GEORGE H. HOLDEN, OF BURLINGTON, VERMONT.

DESIGN FOR A STOVE.

SPECIFICATION forming part of Design No. 32,754, dated May 29, 1900.

Application filed May 2, 1900. Serial No. 15,275. Term of patent 14 years.

To all whom it may concern:

Be it known that I, GEORGE H. HOLDEN, a citizen of the United States, residing at Burlington, in the county of Chittenden and State 5 of Vermont, have invented and produced a new and original Design for Stoves, of which the following is a specification, reference being had to the accompanying drawing, in which the figure is a perspective view of a 10 stove embodying my new design.

The leading feature of my design consists in the design forming the subject-matter of the accompanying illustration.

The design is characterized by the main or 15 body portion A and the top portion B, which extends rearwardly beyond the body A with the top plate C, which also covers the body A, corrugated transversely at D and arching slightly from side to side. The front A' of the body 20 A has the inclined projections E and F near

its top and bottom, and the base of the body is extended forward at G. The side plates of the body A are decorated by series of openings H, represented as diamond-shaped. The front plate A' of the body A is of greater area 25 than the elevation of said body and extends at A² above the corrugated top plate C, as shown.

Having thus described my invention, what I claim as new, and desire to secure by Letters 30 Patent, is—

The design for a stove as herein shown and described.

In testimony whereof I have signed my name to this specification in the presence of 35 two subscribing witnesses.

GEORGE H. HOLDEN.
